United States Patent

Des. 238,468
Patented Jan. 20, 1976

238,468

TOILET TISSUE HOLDER

Arthur E. Bauman, 764 Johnston St.,
Akron, Ohio 44306

Filed Nov. 1, 1973, Ser. No. 411,910

Term of patent 14 years

Int. Cl. D23—02

U.S. Cl. D6—97

FIG. 1.

FIG.2.

FIG. 1 is a front perspective view of a toilet tissue holder embodying the new design.

FIG. 2 is a front perspective view of a variation of the design of FIG. 1.

The undisclosed rear sides of the toilet tissue holder are flat and unornamented.

I claim:

The ornamental design for a toilet tissue holder, substantially as shown and described.
